CLAIM

The ornamental design for a wind turbine structure, as shown and described.

DESCRIPTION

FIG. 1 is a front view of a wind turbine structure showing my new design in a first configuration;

FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a first perspective view thereof;
FIG. 8 is a second perspective view thereof;
FIG. 9 is a front view in a second configuration;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a first perspective view thereof;
FIG. 16 is a second perspective view thereof;
FIG. 17 is a front view in a third configuration;
FIG. 18 is a rear view thereof;
FIG. 19 is a left side view thereof;
FIG. 20 is a right side view thereof;
FIG. 21 is a top view thereof;
FIG. 22 is a bottom view thereof;
FIG. 23 is a first perspective view thereof;
FIG. 24 is a second perspective view thereof;
FIG. 25 is a right side view in the first configuration with the outer frame removed;
FIG. 26 is a top view in the first configuration with the outer frame removed;
FIG. 27 is a third perspective view in the second configuration;
FIG. 28 is a third perspective view in the third configuration;
FIG. 29 is a fourth perspective view in the third configuration;
FIG. 30 is a fifth perspective view in the third configuration;
FIG. 31 is a sixth perspective view in the third configuration with the outer frame removed; and,
FIG. 32 is a front view in the first configuration with the outer frame removed.
The broken lines shown depict the portions of the wind turbine structure that form no part of the claimed design. The outer frame of the wind turbine structure in FIGS. 25, 26, and 31 was removed for clarity regarding the claimed portions obstructed by the frame in FIGS. 4, 5, and 1, respectively.
